FURNACE HEATING CONTROL

Elmer K. Hansen, Edgewood, Pa., assignor to
 Westinghouse Electric & Manufacturing Company, East Pittsburgh, Pa., a corporation of Pennsylvania

Application August 13, 1938, Serial No. 224,713

9 Claims. (Cl. 266—5)

My invention relates broadly to the control of the rate of circulation of an atmosphere about a charge being heated in a furnace, preferably, although not necessarily, an electric furnace.

Many furnaces employed for heat treatment, circulate a gaseous medium of known and desired composition about the charge therein, primarily to prevent deleterious effects upon the charge by ordinary products of combustion or by a more common surrounding atmosphere such as air. The protective atmosphere is directed to the heating chamber by means of some gas inlet device and is permitted to leave the heating chamber through some gas outlet means.

One type of furnace usually employing a protective atmosphere is the so-called bell furnace. In this type of furnace a metallic shell or hood completely encloses the charge and the shell rests upon a base in a gas-tight manner. When it is desired to heat the charge, the heating bell is placed about the hood and heat is applied to the exterior surface thereof. The gaseous atmosphere introduced inside the shell is one which will not react chemically with the charge or any constituent or impurity of the charge. An example of a heating process employing a protective atmosphere is the bright annealing of copper. The bright annealing of copper is accomplished at temperatures ranging up to 1200° F. The inert gaseous atmosphere usually comprises in the neighborhood of 14% CO₂, 1% CO, 1% H₂ and the remainder N₂, the gaseous mixture having a dew point of approximately 40° F.

In order to obtain fast heating of the charge and uniform temperature distribution through it, the atmosphere is forcibly circulated about the charge. This is particularly advantageous in processes wherein the heating temperatures are not very high and the heat is transferred to the charge almost entirely or at least to a very large extent by convection. Usually the protective gas is circulated about the charge by a fan within the heating chamber to transfer the heat of the shell to the charge by convection, while the movement of the atmosphere creates the uniform temperature desired. Conversely, during cooling of the charge the circulated atmosphere may be employed to increase the rate of cooling and at the same time maintain a more even temperature distribution through the charge. Because of the circulation of the atmosphere the heat treatment cycle can be better controlled, and a more uniform product obtained than would be the case without a rapid circulation of the atmosphere.

However, fans are not employed in furnaces to the extent that might be desired for the reason that they must be constructed of a material to withstand the high stresses due to centrifugal forces. These materials are generally metallic and rapidly lose their strength with increase in temperature. Thus, an alloy composed of 25% chromium and 10% nickel with the remainder iron can withstand a stress of 2000 pounds per square inch for a 1% creep in 10,000 hours at 1800° F. but will give a similar creep under a stress of only 760 pounds per square inch at 2,000° F. At temperatures below 1800° F., the permissible stress for a 1% creep and 10,000 hours of operation increases quite rapidly while at temperatures above 2000° F. the permissible stress fast approaches zero.

In order to employ fans in furnaces where their permissible stress is a serious factor, it has heretofore been necessary to construct a fan with an exceptional amount of heat resistant metal or to run a smaller fan at a very low speed. The former instance, of course, results in an expensive fan construction, while the latter results in an increased time for the heating cycle.

It is, accordingly an object of my invention to obtain a faster heating cycle in furnaces employing the circulation of a gaseous atmosphere around the charge.

It is a further object of my invention to so operate a fan that is employed to circulate the gaseous atmosphere within a furnace at a more rapid rate when the fan can withstand larger stresses at the lower temperatures and at a smaller rate when the fan cannot withstand such large stresses.

I find that the control of the speed of the fan and, therefore, the rate of circulation of the gaseous atmosphere within the heating chamber is particularly advantageous and applicable with decided improvement to processes where the gaseous medium is circulated about a fluid metal as, for example, in brazing. In such processes the work at hand may require that the brazing substance be exposed to the circulating atmosphere. So long as the brazing substance is solid a high rate of gaseous circulation may be employed with an attendant high heating rate and uniform temperature distribution. When, however, the brazing substance softens and becomes liquid, too high a rate of circulation of the gaseous atmosphere may blow the molten fluid away from the adjoining surfaces which are to be brazed. By controlling the speed at which the atmosphere circulates so that the rate is low just

before the melting point of the brazing substance is reached, the heating cycle may be hastened up to that point, and, conversely, the cooling cycle may also be hastened below that point.

- 5 It is an additional object of my invention to control the speed of rotation of a fan circulating a gaseous medium in a heating chamber by factors which involve allowable stresses in the fan or by factors which involve the allowable rate 10 of circulation of the medium about a charge at the instant furnace temperature, or a combination of both.

Other objects and features of my invention will be apparent from the following description thereof taken in conjunction with the drawings in which:

Figure 1 is a cross section of a bell type furnace employing the principles of my invention;

Fig. 2 is a part top view of the fan;

20 Fig. 3 is a part top view of the charging support plate;

Fig. 4 is a schematic electrical wiring diagram for a two-speed control of the fan motor;

25 Fig. 5 is a diagram similar to Fig. 4, but showing a multi-speed control of the motor; and

Fig. 6 is a curve showing permissible working stress against temperature of two heat resistant iron alloys.

In Figure 1, I have shown my invention applied to a bell type furnace, but it is to be distinctly understood that I do not desire to be limited to this type of furnace, and that the bell furnace has been chosen merely as a vehicle by which to illustrate my invention. In this figure, 30 the bell 1 removably rests upon a base 2, and is constructed with heating units 4 at the sides thereof and heating units 6 centrally therein.

A charge supporting plate 8 is supported by the base 2 and is annular in general shape. The 40 charge such as 10 in this instance comprises coils of wire resting upon the top of the charge supporting member 8. A hood 12 is placed about the charge and has a turned flange member 14 extending into a liquid seal 16, so that a gas-tight 45 enclosure is provided within the shell 12.

The furnace may be of any desired cross section, but the one being described is of circular cross section. The hood 12, therefore, comprises an inner cylindrical member 18 and an outer 50 cylindrical member 20, the two forming an enclosed space 22 comprising the heating chamber. While I have shown my invention applied to a furnace having a central heating unit and hood shaped to correspond, I do not wish to be limited 55 to any particular type of furnace. As a matter of fact, my invention is admirably suited to a bell furnace with the central heating units omitted and the hood shaped accordingly.

An annular plate 24 seals the chamber at the 60 top thereof and a dish-shaped member 26 closes the bottom of the cylindrical shell member 18. The latter element is spaced above the furnace base 2 for a purpose which will later become apparent. Suitable expansion and contraction expedients (not shown) may be employed, if necessary, as is well known to the art.

In this furnace the base 2 has a central aperture through which extends a shaft 28 having attached thereto at its end within the interior 70 of the furnace a fan 30 of the centrifugal type. The shaft may be guided and supported in lubricated bearings in a supporting structure generally indicated by the reference character 32 which may be in any appropriate form forming a gas-tight fit with the base. A preferred construc-

tion is disclosed in the application of F. Davis, Serial No. 221,719, filed July 28, 1938, assigned to the Westinghouse Electric & Manufacturing Company. The shaft 28, and therefore the fan 30, are driven by a motor 34 through the medium 5 of pulleys 36 and belts 38. I show the motor 34 supported by the furnace base at the exterior thereof, as, for example, by I-beams 40, but it is obvious that the fan and shaft may be driven by any appropriate means. However, I employ a 10 motor because of the flexibility of the control thereof.

The fan which I employ, as aforementioned, is of the centrifugal type and has a central opening 42 which serves as an entrance for gas, and 15 blades 44 which serve to discharge the gas radially in all directions. A bottom plate 46 covers the bottom of the fan in its entirety. The blades 44 are formed integrally with this bottom 46 and a top annular plate 48, the open central portion 20 of which comprises the inlet 42.

The fan discharges in the general direction of the charge supporting member 8, the latter being webbed to provide passages through which the gaseous medium discharged from the fan may 25 pass.

As shown more particularly in Fig. 3, the charge supporting plate comprises an annular member 50 integral with I-shaped ribs 52 protruding radially. The ribs are circumferentially spaced to 30 permit passage of the atmosphere upwardly therethrough or into contact with the bottom of the charge if the latter completely covers the tops of spaces 54 between the ribs.

A gas inlet 56 directs the protective atmosphere 35 into the central aperture of the base and a gas outlet 58 permits the escape of the gaseous atmosphere. Valves (not shown) may control the flow through the inlet and outlet pipes. Normally only an amount of gas is permitted to escape from the outlet pipe sufficient to keep the protective atmosphere clean and pure.

The path of the gaseous medium circulated by the fan is indicated by the arrows 60. The gaseous atmosphere discharged from the fan passes through the charge supporting member 8 and then rises along the outside of the charge 10, passes over the top thereof, and down the inner side of the charge to the fan inlet opening 42.

When the charge is just being heated and the temperatures low, it may be desirable to circulate the medium at as rapid a rate as possible in order to shorten this part of the heat treatment cycle. For a fan of approximately 30 inches diameter and a discharge of 60 cubic feet per second, a speed of rotation of 1500 R. P. M. may be employed initially. As the temperature rises, the fan loses its strength and, in Fig. 6, I show a typical curve of a heat resistance metal of a nickel-chrome-iron alloy showing the permissible working stress for temperature ranges between 1200° and 2000° F. It may be observed that starting with exceptionally high stresses at low temperatures, the allowable stress drops rapidly to about 1700° F. Thereafter the rate of decrease of permissible working stress is considerably slower, but nevertheless the values thereof are now so low as to prevent the application of any appreciable load to the fan. The curves are 70 typical of practically all heat resistant metals, and by my invention I seek to employ the fan at its utmost efficiency, taking into consideration the fact that at the higher temperatures the fan may be so weak that it can safely impart only 75

low velocities to the circulating gaseous atmosphere. I accomplish this by running the fan at higher speeds when the temperatures to which it is submitted are relatively low and its permissible working stress high, and at low speeds when the permissible working stresses decrease.

In Fig. 4 I show one scheme by which this may be accomplished in a somewhat rough manner. A thermocouple 62 is subjected to the temperature of the gaseous medium and has leads 63 connecting to a pyrometer 64. This pyrometer has a single pair of contacts 66 which close when a predetermined temperature is reached dependent upon the adjustment of the pyrometer. When the predetermined temperature is reached the contacts 66 close to energize a relay 68 having a normally open contactor 72.

At low temperatures the motor 34 has its armature 74 directly connected between the power leads and its field 76 connected between the power leads through a resistance 78. When the relay 68 is energized it closes its normally opened contactor 72 to parallel a second resistance 80 across the resistance 78 and thereby decrease the speed of the motor 34 by increasing the strength of its field. The resistance 78 is made adjustable so that the initial speed of the motor may be controlled, and if desired, the second resistor 80 may also be adjustable to control the speed at the lower limit.

The maximum or minimum values of speed will necessarily depend upon the particular heating process employed. If the process is such as to permit of the higher speed of rotation of the fan throughout the cycle, then obviously my invention need not be employed, but if the process is such as to require a lower speed of rotation of the fan at some point in the cycle and for some extent within it, then my invention provides a means wherein the cycle is hastened. Thus, during the early stages of the cycle when the charge is being heated or in the later stages when the charge is being cooled, the fan may rotate at its maximum velocity, whereby a most efficient transfer of heat is accomplished between the shell and the charge. I may, therefore, employ a higher heating rate in the heating elements 4 and 6 during the heating stage.

When the temperature is reached at which it is advisable to decrease the stresses within the fan, the thermocouple will operate the pyrometer previously adjusted to energize the relay 66 at this temperature, and the resistance 80 will be inserted in the motor field circuit in parallel with the resistance 78 and thereby decrease the speed of the fan. In cooling, of course, the reverse is true, the pyrometer opening the contacts 66 to deenergize the relay 68 and increase the fan speed when the temperature has dropped to the desired value.

The two-speed control is of particular advantage in phosph-copper brazing in which the brazing substance melts at approximately 1550° F. At this temperature the fan has appreciable strength if it is formed of an iron alloy comprising 35% nickel and 15% chromium, so that ordinarily we may suppose that the maximum rate of circulation of the gaseous atmosphere may be employed throughout the process. However, where the brazing is to be accomplished between objects of such conformation that the brazing substance is exposed to the gaseous atmosphere, then too high a speed of gaseous circulation may blow the brazing substance away from the desired joint when the brazing substance

melts. Accordingly, it may be desired to adjust the pyrometer to close the contacts 66 at a temperature somewhat below the melting point of the brazing compound, in this instance, say, 1500° F. My invention, therefore, has application to processes in which the permissible working stress of the fan is not involved.

In steel to steel brazing, temperatures in the neighborhood of 2050° F. are common. In this instance, of course, the permissible working stress of the fan is of greater importance than the prevention of the blowing of the molten brazing copper away from the joint surfaces it is desired to braze. A combination of both factors may, therefore, determine the setting of the pyrometer 64.

In Fig. 5, I show a modification of the motor control in which the speed of the motor is controlled in a greater number of steps than that shown in Fig. 4. The contacts 82, 84, 86 and 88 are engaged by a contact 89 at different temperatures, in turn, to control relays 90, 92, 94 and 96, respectively. During the increase in temperature part of the heating cycle, elongated contact 89 will first engage contact 82 to cause insertion of resistance 98 in the armature circuit of the motor 34. Subsequently, at some higher temperature, the contact 84 will be engaged to cause insertion of an additional resistance 100 in the armature circuit of the motor 34. With further increase in temperature, engagements of contact 86 and then contact 88 by contact 89 energize relays 94 and 96, respectively, to further decrease the speed of rotation of the fan motor 34 by the insertion of resistance in the armature circuit.

From the diagram of Fig. 5 it is obvious that each of the relays 90, 92, 94 and 96 when energized by their controlling contacts of the pyrometer 102 remove shorts about the sections of resistance in series with the armature of the motor 34. I prefer to employ the control system of Fig. 5 in the heating cycles in which the temperatures are relatively high, as, for example, temperatures up to approximately 2000° F.

The contact 89 is of a length sufficient to span all four contacts 82, 84, 86 and 88. During the rising temperature portion of the heating cycle, each contact 82, 84, 86 and 88 is engaged by the contact 89 at the adjusted temperature for which engagement is to take place, and remains engaged until the temperature again falls below the aforesaid adjusted temperature.

Although the above described modifications all show wherein the motor speed is lowered at the appropriate value or values of high temperature, it is obvious that at any value the motor circuit can be entirely opened to stop rotation of the fan entirely. The manner of accomplishing this is at once obvious and can be accomplished with a relay such as 96 opening the motor circuit instead of varying the speed of the motor. Or in brazing an embodiment such as that of Fig. 4 may be employed with the controlling relay opening the motor energizing circuit instead of increasing the field current.

While Figs. 4 and 5 show a direct current motor whose speed is controlled in the one instance by the resistance in the field and in the second by the resistance in the armature, it is obvious that any type of speed control may be employed. Moreover, the method of speed control will depend largely on the type of fan drive being used and I do not desire to be limited in any way to a particular expedient employed for controlling

the rate of circulation of the gaseous atmosphere within the furnace.

While I have illustrated my invention in the form which I believe to be the best mode of application thereof, it is obvious that many changes may be made within the spirit and scope of the novel system which I have introduced. It is desired, therefore, that the appended claims be given the broadest construction and limited only by the prior art.

I claim as my invention:

1. A heat treatment furnace having a heating chamber characterized by an atmosphere about a charge being heat treated, a fan for circulating said atmosphere, and means for varying the speed of said fan from one speed to another responsive to temperature conditions within said heating chamber.

2. A heat treatment furnace having a heating chamber characterized by an atmosphere about a charge being heat treated therein, a fan subjected to the heat in said chamber for circulating said atmosphere, and means to vary the speed of said fan from one speed to another responsive to temperature conditions within said heating chamber, reversely as compared to temperature variations, within said heating chamber.

3. A furnace including heating means, an enclosed charge heating chamber, means for per-
30 vading said chamber with a gaseous atmosphere, a metal fan in said heating chamber for circulat-
ing said atmosphere, a thermocouple subjected
35 to the heat of said atmosphere, means including
a motor outside said chamber for driving said fan,
and means operable by said thermocouple for
varying the speed of said motor from one speed
to another reversely to temperature changes of
said thermocouple so that said fan is rotated at
higher speeds when its strength is greater.

4. The method of employing a metallic fan in
a heating chamber for circulating an atmosphere
about a charge in said chamber, which comprises
rapidly rotating said fan while the temperatures
45 of said atmosphere are relatively low and the
strength of the fan relatively large, and decreas-
ing the speed of rotation of said fan when the
temperatures have become higher and the
strength of the fan relatively lower.

5. The method of employing a metallic fan for
50 circulating an atmosphere in a heat treating
furnace chamber which comprises rotating said
fan while the temperatures are higher at a speed
commensurate with the lower strength of said

fan at the said high temperatures, and increasing
the speed of the fan when the temperatures have
become relatively lower and the strength of the
fan greater.

6. A heat treating cycle involving circula- 5
tion of a protective atmosphere about a charge
which comprises confining said charge in a
chamber, applying heat to said chamber, circulat-
ing the protective atmosphere about the charge
in said chamber at a rapid rate when the tem- 10
perature of said charge is to be changed rapidly
and at a slower rate thereafter.

7. In the method of brazing two metallic sub- 15
stances with a brazing metallic substance which
comprises heating said substances in brazing re-
lation in a gaseous atmosphere, circulating said
atmosphere about said substances at a rapid rate
while the temperature is below the melting
point of said brazing substance and decreasing
said rate when said melting point is approached 20
whereby the circulating atmosphere will not blow
the melted brazing substance when the last melts.

8. A heat-treatment furnace having a chamber
in which a charge is to be heat-treated in ac-
cordance with a cycle involving increasing or 25
decreasing the temperature of the charge, the
furnace having provisions so that the charge
may be enveloped by a protective atmosphere,
said furnace being provided with energy-chang- 30
ing means for changing or maintaining the tem-
perature of said charge and atmosphere, means
to circulate said atmosphere, and means for con-
trolling the rate of said circulation responsive to
temperature in said furnace so that a relatively 35
higher rate obtains at relatively lower tempera-
tures, and a relatively lower rate at higher tem-
peratures which are in proximity to that at which
the charge is to be or is maintained whereby that
part of the cycle involving change of tempera- 40
ture of the charge is increased, especially where
a cold charge is first brought into a hot furnace.

9. In a device of the class described, a furnace
base, a hood on said base forming therewith an
enclosed heating chamber, a heating bell about
said hood, means for discharging a protective 45
atmosphere to permeate said chamber, a metal
fan in said chamber for circulating said atmos-
phere in said chamber, driving means for said
fan comprising a motor heat-insulated from said
chamber, and temperature responsive means in 50
said chamber for controlling said motor to con-
trol the speed of said fan.

ELMER K. HANSEN.
